UNITED STATES PATENT OFFICE

HISAKICHI TAHARA, OF TOKYO, JAPAN

MOVABLE DAM

Application filed June 30, 1928, Serial No. 289,565, and in Japan February 8, 1928.

This invention relates to improvements in the operation of dams and the like. With rolling dams of a length beyond one hundred feet, it has hitherto been considered impossible to move the dam up and down in a horizontal condition by transmitting uniform rotary movement from one end to the opposite end with a single hoisting machine, and driving forces were applied at both ends by separate wire ropes and hoisting apparatus. Due to the different elongations of the separate wire ropes or cables it was necessary to adjust the speed of each hoisting machine, and, even where the two ropes had the same tension, it was difficult to operate each hoisting machine uniformly. For such reason, it will be obvious that the trouble of adjustment and expense of the plant will be reduced if the dam is operated with a single wire rope or cable and hoisting machine, and the object of the invention is to provide such a system.

The invention consists in the use of a single wire rope or cable running over a number of pulleys provided to the same number on the hanging journals in the ends of the dam and at the left and right sides of the bridge on the side walls of the gate: one end of the rope or cable connecting to a fixed point of the inclined abutments and the other secured to the drum of the hoisting machine. Rollers are provided at both ends of the dam, in the form of rolling wheels engaged with guide rails upon the inclined surfaces or abutments of the gate, gear wheels being geared to racks on the inclined abutments. These gears and racks may be replaced by two sets of hanging and anchored chains which run in opposite directions over the circumference at the ends of the dam.

In the case of a flood, when gear wheels and racks are used lack of balance of the up and down motions of the dam or breakage of the teeth or stoppage of the hoisting machine and motor may be caused if floating logs, earth or the like is engaged in the gearing, while when chains are used such defects will not develop.

The annexed drawings show apparatus

by way of example for carrying into effect the present invention.

Fig. 1 shows an end view of the apparatus according to the invention, Fig. 2 is a sectional front view on the line II—II of Fig. 55 1. Figs. 3a and 3b are end views of the dam having a hanging chain and an anchored chain on the driving end. Figs. 4a and 4b are views of the opposite end. Figs. 5 and 6 are perspective views of the hoisting rope 60 or cable according to the invention.

In the present invention, as with the usual rolling dam a gear wheel 1 and roller 2 may be provided at the ends of the dam, wheel 1 engaging with the rack 4, and roller 65 2 resting upon the rail 5: these racks and rails are laid upon the inclined surfaces or abutments of the gate. As shown in Figs. 3a, 3b, 4a and 4b, two sets of hanging chains and the anchored chains may be used instead of the racks and wheels, these chains being arranged at both ends of the dam. The upper end of the hanging chain B is connected adjustably by a turnbuckle to a fixed point 15 of the inclined surface of the gate and the lower end is fixed to a point 16 on the circumference of the dam adjacent the lower part of the inclined surface. One end of the anchored chain C is fixed to a point 17 forward of the point 16 and the other end connects with a fixed point 18 at the lower part of the gate, running over about $\frac{3}{4}$ of the circumference of the dam. It will be understood from the drawings 70 75 80 85 that rotations in opposite directions will be given to the dam each time the latter is pulled up and down, because the hanging chains and the anchored chains pull the dam by respectively opposite forces. That is to say, when the dam is pulled up the anchored chains are wound off, while the hanging chains are wound round the dam and when the dam is pulled down the hanging chains and anchored chains are 90 95 inversely operated.

In Figs. 1 and 2, the numerals 6, 6' and 6'' designate three axles which are suitably fixed to the bridge on the gate. On these axles a number of pulleys 7, 7', 77'' and 8, 100

8', 8" are provided so that they may revolve independently and at the underneath of the fixed axles 6, 6' are provided the hanging journals 9, 9' which carry the axles at the 5 ends of the dam: these hanging journals carry axles 10 within the same vertical planes as the fixed axles 6 and 6' (see Fig. 1). The axles 10 carry sets of pulleys 11, 11' and 12, 12', the latter being supported so as to be independently rotated.

One end of the wire rope or cable 13, connects to a fixed point 14 at the side of the hoisting machine, from which it is run over the pulleys 12'-8"-7'-11'-7-11-7"-8"-12-8 as shown in Fig. 2, and the other end of the rope or cable is connected to the drum of the hoisting machine. When the hoisting machine is operated and the end of the rope is wound up, the pulling force 20 will be transmitted with equal speed through the length of the rope or cable 13 to both ends of the dam. Though the pulley 12 which receives the force through the rope from the hoisting machine is to be pulled 25 up first, the movement of the pulley 12 will be delayed because the pulley 12' on the same axle will receive the pulling force at the last moment by the arrangement of the rope, and the pulley 12 waits without moving until the 30 pulleys 11, 11' at the opposite side begin to be pulled up. As soon as the pulleys 11, 11' are pulled up, the pulleys 12, 12' are also pulled up with the wheels 1 and the dam is rolled up along the guide rails 5.

35 Where hanging chains and anchored chains are used instead of the gears and racks, it will be understood from the above that rolling motion is given to the dam in the same way.

40 The relative speeds of the rope at the ends of the dam are as follows:—In Fig. 5, if the weight W of the dam is on the axle X , and the rope is run over several pulleys in the order $a, b, c, d, e, f, g, h, i, j, k$ from 45 the fixed point o and k is connected to the hoisting machine, the speed of winding, that is to say, the ratio of speed of the beginning and end of the rope will be 1:8.

Thus the sums of the respective speeds of 50 the longitudinal portions of the rope at the left and right sides of the dam are equal and the respective tensions of the said longitudinal portions are equal because the number of turns of the rope at the left and right 55 sides is the same. Now as the longitudinal portions of the rope have the same tensions and speeds and the weights on those portions are the same, both ends of the dam will be pulled up uniformly. 60 Though the above explanation has been given for the case where two pulleys are provided at the sides of the dam, it will be understood that where the number of pulleys is increased to more than two, the operation 65 will be similar to the above. Where, how-

ever, the number of pulleys has been increased to more than two, it will sometimes be seen that the sums of the speeds of the longitudinal portions of the rope at the left and right sides are not equal, the gear wheels are of extraordinarily large diameter in comparison with the speed of the dam, and the said gears revolving themselves in mesh with the racks, such differences of speed would be automatically adjusted by the slip 75 between the pulleys and their axles.

The explanation hereinbefore given also applies to the case where hanging and anchored chains are adopted. Since the friction produced between those chains and the 80 dam acts against the rolling of the dam slip will occur between the suspension pulleys and their axes. In view of such a slip, the differential speed of the longitudinal portions of the cable at both sides will be adjusted as in the above case.

What I claim and desire to secure by Letters Patent is:

1. A movable dam, comprising axles and mounted at its ends in journals for rotatable movement; supports for the journals and pulleys operatively mounted in said supports; a separate set of pulleys operatively mounted in a bridge support and a gate to receive said support; a single suspension 95 cable operative with both sets of pulleys, one end of said cable being connected to a fixed point and having operative connection to a hoisting means at its opposite end.

2. A movable dam, provided with axles 100 and mounted in journals at its ends for rotatable movement on said axles; hanging supports for said journals and pulleys operatively mounted in said supports, said pulleys constituting a system of equal numbers at each end of said dam; a separate system of pulleys mounted in a bridge support in opposing relation to said first-named system of pulleys; a gate bridged by said support; and a single suspension cable 105 operative with both systems of pulleys, one end of said cable being connected to a fixed point in the gate and having operative connection at its opposite end to hoisting means to effect movement of said dam.

3. A movable dam provided with axles at its ends and journaled for rotatable movement on said axles; supports for said dam and pulleys operatively mounted in said supports at each end of the dam; a separate system of pulleys in opposing relation to the first-named pulleys and a bridge support for said pulleys; a gate bridged by said support; a single cable operative with both systems 110 of pulleys to effect movement of the dam; a set of hanging and anchored chains operatively associated with said dam adjacent its ends, the upper end of each hanging chain being connected to a fixed point at the top 115 of the inclined abutments of said gate and 120 125 130

the lower end being fixed to a point on the periphery of the dam, one end of each anchored chain having fixed connection at points on the periphery of the dam.

4. A movable dam, comprising axles and mounted at its ends in journals for rotatable movement; supports for the journals and pulleys operatively mounted in said supports; a separate set of pulleys operatively mounted in a bridge support and a gate to receive said support; and a single suspension cable operative with both sets of pulleys, one end of said cable being connected to a fixed point and having operative connection to a hoisting means at the opposite end, and the fixed end of the driving cable being at the same side with the driving end of the cable and the cable passing over the pulleys of one side and then over those of the other side.

20 In testimony whereof I have signed my name to this specification.
